UNITED STATES PATENT OFFICE.

HARRISON B. WALTER, OF DANVILLE, ILLINOIS, ASSIGNOR TO NATIONAL FIBRE BOX COMPANY, OF DANVILLE, ILLINOIS, A CORPORATION OF ILLINOIS.

BOX HAVING SOLID ENDS.

1,125,782.

Specification of Letters Patent.

Patented Jan. 19, 1915.

Application filed June 28, 1912. Serial No. 708,008.

To all whom it may concern:

Be it known that I, HARRISON B. WALTER, a citizen of the United States, residing at Danville, in county of Vermilion and State 5 of Illinois, have invented certain new and useful Improvements in Boxes Having Solid Ends, of which the following is a specification.

My invention relates to an improvement 10 in boxes having solid ends, and the object is to provide a body and ends so that the edges or corners of the ends and body will be straight. This is accomplished by creasing the body of the box at the folding point 15 for forming the four sides in such a manner that the edges of the sides when brought together will produce a straight edge on the interior of the box.

The invention consists in certain novel 20 features of construction and combinations of parts which will be hereinafter fully described and pointed out in the claims.

In the accompanying drawings, Figure 1 is a view of the body of the box in its 25 collapsed or flattened-out position before being folded; Fig. 2 is a view of the blank forming one of the ends or heads; Fig. 3 is an enlarged detail sectional view through the body of the box showing the scoring; 30 Fig. 4 is an enlarged detail plan view showing the scoring along the outer edges of the body for forming a bead to support the heads; Fig. 5 is an enlarged detail plan view showing the head applied to the box and 35 indicating how the head fits and conforms to the interior of the box; Fig. 6 is an enlarged detail sectional view showing the manner of mounting the head on the bead formed along the outer edges of the body.

40 A. represents the body of the box, which is made from a single piece of material, and is provided with grooves 1, 1, at the several corners, which grooves are formed by creasing or scoring the body of the box, 45 producing beads on the outer surface of the box. The grooves 1 allow the several sides of the box, 2, to be bent into position for forming or assembling the box from its collapsed condition, and bring the adjacent 50 edges of the sides in close proximity to each other, thereby producing a straight edge at each corner of the box.

The heads or ends 3 are provided with flanges 4, 4, and 5, 5, the flanges 4, 4, being of greater length than the heads or ends, 55 and adapted to engage and overlap the ends of the flanges 5, whereby a straight edge or corner is formed at each corner of the head, so that the head will conform and fit snugly within the inner walls of the box. Each 60 flange is provided with a groove or depression 6 on the under side thereof, forming the bead 7 on the upper side thereof, the adjacent ends of the several flanges being brought together when the adjacent ends of 65 the sides are brought together, the beads tending to exert an outward pressure upon the flanges whereby they will be compressed and frictionally engage the walls of the 70 box. The flanges 4 and 5 can be fastened to 75 the walls of the box in any suitable manner.

From the foregoing it will be seen that by providing a groove at the four folding edges of the box, the adjacent edges of the sides can be brought together for forming 80 a straight edge at each corner, and that the flanges of the heads or ends can be made of proper length by notching the heads sufficiently to make two of the flanges of the same width as the head and the other two 85 flanges of a greater length than the head, so that when the flanges are brought to an upright position, the longer flanges will overlap the ends of the shorter flanges, thereby producing a straight edge for fitting the corners of the box.

Having fully described my invention, what I claim as new and desire to secure by Letters Patent, is:

1. A closure for boxes comprising a head 90 having flanges formed thereon adapted to be bent at an angle to the head, said flanges having grooves formed therein adjacent to their folding edges for producing beads on the opposite side of the flanges, said beads 95 located at the juncture of the head and its flanges and extending inwardly for forcing the flanges outward and away from the edges of the head when the flanges have been bent at an angle to the head. 100

2. A closure for boxes comprising a head having flanges formed thereon, beads on the flanges located at the juncture of the head and the flanges and extending inwardly for

causing the flanges to be forced outward and away from the edges of the head when the flanges have been bent at angle to the head.

3. A closure for boxes comprising a head having flanges thereon, beads formed at the edge of the flanges at the juncture of the head and the flanges, and extending inwardly, the ends of the adjacent beads adapted to be brought together when the

flanges are bent at an angle to the head, ¹⁰ whereby the beads will cause the flanges to be forced in an outward direction.

In testimony whereof I affix my signature, in the presence of two witnesses.

HARRISON B. WALTER.
